UNITED STATES PATENT OFFICE.

LEVI FISHER, OF BRANTFORD, CANADA.

GANG-PUNCH.

SPECIFICATION forming part of Letters Patent No. 599,997, dated March 1, 1898.

Application filed October 16, 1897. Serial No. 655,433. (No model.)

To all whom it may concern:

Be it known that I, LEVI FISHER, of Brantford, in the Province of Ontario and Dominion of Canada, have invented certain new and useful Improvements in Gang-Punches, of which the following is a full, clear, and exact description.

The object of the invention is to provide certain new and useful improvements in gang-punches whereby the punches and dies can be readily adjusted according to the work on hand and securely locked in position to insure proper punching.

The invention consists principally of a punch-stock fitted in a head and adapted to carry a pressure-pin engaged by the punch and a coupling screwing on the punch-stock for pressing the pin in engagement with the head and for clamping the punch-stock in place on the head.

The invention further consists of longitudinally-split die-holders arranged to receive and hold the dies and fitted loosely in a groove formed in a base-block and a pressure-bar fitted into the said groove and engaging with its inner beveled edge the forward faces of the die-holders.

The invention also consists of certain parts and details and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a front elevation of the improvement. Fig. 2 is a plan view of the base and dies supported thereon, parts being broken out. Fig. 3 is a cross-section of the head with the punch and its holding device in place, and Fig. 4 is a cross-section of the base on the line 4 4 of Fig. 2.

The improved gang-punch illustrated in the drawings is mounted on the usual frame A, supporting a base-block B, supporting the dies C, over which operate punches E, carried by a reciprocating head D, bolted or otherwise fastened to the ram of the machine. Each of the dies C is removably held in a longitudinally-split die-holder F, the sections of which are connected with each other by transversely-extending dowel-pins F', as is plainly

indicated at the right in Fig. 2 and in dotted lines in Fig. 4.

The front and rear edges of each die-holder F are beveled and rest in a longitudinally-extending groove B', formed in the top of the base-block B, the said groove opening at its middle into an aperture B² for the passage of the punched-out material. The rear bevel of each die-holder F fits into the correspondingly-beveled wall B³ of the groove B', and the front bevel of each die-holder is engaged by the inner correspondingly-shaped end of a pressure-bar G, fitted to slide laterally and guided for this purpose on screws H, screwing into the base-block B and having their heads in countersunk recesses formed in the bar G. Set-screws I screw in the base-block B and abut against the pressure-bar G to move the latter in a transverse direction against the several die-holders F, so as to securely lock the same in place on the top of the base-block B after the dies in the die-holders are in proper position relatively to the punches and the work under treatment. A cover-plate J is attached to the top of the base-block B for covering up the joint between the base-block and pressure-bar and also the heads of the screws H, as is plainly indicated in Fig. 4.

Now it will be seen that by the arrangement described the operator upon slightly unscrewing the set-screws I releases the die-holders F sufficiently to permit of sliding the same longitudinally in the groove B' until they are moved to the desired position, according to the nature of the work on hand, and then the operator screws up the screws I to move the pressure-bar G against the die-holders, so as to securely lock the same in place in the groove B' and at the same time clamp the die in place on the die-holder, owing to the split nature of the latter.

On the top of the base-block B, near the rear end thereof, is arranged a longitudinally-extending dovetailed groove B⁴, adapted to be engaged by correspondingly-shaped heads K' of bolts K, each engaging a stripper L, projecting with its forward forked end L' over a corresponding die C to hold the work in position during the return movement of the punch E, which latter passes freely through the open portion of the forked end L'.

The rear end of each stripper L is provided with a downwardly-extending foot L², adapted to rest on the rear portion of the base-block B, as is plainly shown in Fig. 4, the stripper 5 itself resting on a gage N, formed of two longitudinally-extending bars connected with each other at their ends by cross-blocks, as is plainly shown in Fig. 2.

The bars of the gage N are formed with 10 transversely-extending registering apertures for a gage-pin O, the head O' of which forms a rest for the inner edge of the work under treatment, each pin being held on an eyebolt P, extending upwardly between the two bars 15 of the gage N, the nut P' resting on the top of a washer P², located on the top of the gage N, so that when the nut P' is screwed up the pin O is securely locked in place in the gage N. By unscrewing the nut P' the pin O may be 20 readily adjusted laterally, according to the distance the holes are to be punched from the inner edge of the work under treatment.

Now it will be seen that by the arrangement described the strippers L can be readily adjusted in a longitudinal direction, according to the position of the die-holders and dies, and the gage-pins O can be readily adjusted transversely, according to the nature of the work under treatment, as above mentioned. The gage N is of a suitable length, so as to readily accommodate the work and insure a proper support and gage for the same while undergoing punching.

In order to support the punches E and to 35 properly adjust the same in a longitudinal direction relatively to the dies C, I provide the following device: The head D is formed on engaged by correspondingly-shaped punch-hits under side with a dovetailed groove D', stocks Q, each formed with a cylindrical projection Q', threaded to receive a coupling R, adapted to support the head E' of the corresponding punch E, the said head abutting with its top face against a pin S, fitted to slide vertically in the punch-stock Q. The upper end of the pin S is formed with a conical head S', fitting loosely in a corresponding aperture in the punch-stock and adapted to abut with its upper face against the under side of a steel-plate backing or lining T, fastened by screws 50 to the head D at the bottom of the dovetailed groove D', as is plainly indicated in Fig. 3.

Now it is evident that when the coupling R is screwed outward the punch-stock Q can be readily shifted longitudinally in the groove D', so as to bring the punch E in proper alignment with the opening in the die C. When the desired place has been reached, then the coupling R is screwed up to cause the head 60 E' of the punch to push the pin S upward, so that the head S' of the pin S abuts against the steel lining or backing T, and upon a further screwing of the coupling R the punch-stock Q is caused to move downward, so as 65 firmly clamp or bind in the groove D to securely hold the parts in place.

Now it will be seen that by the arrange-

ment described both the dies and punches may be readily adjusted lengthwise on a punch-press or like machine on which the 70 parts are used, so as to insure proper punching of the work at the desired places.

When the machine is in operation and the ram, with its head D, carrying the punches E, descends, then the latter punch the desired 75 apertures into the work on top of the dies C, the strain on the punches being taken up by the pins abutting with their heads against the steel backing or lining in the head, so that the fastening devices for the punches, consisting of the punch stocks or holders and the coupling, are completely relieved from such strain and are not liable to become loose and displaced, as is so frequently the case as heretofore constructed. The punch stocks 80 or holders may also be locked in place on the head D by a device similar to that for the dies C—namely, by a pressure-bar and set-screws, as above described.

It is evident that a great variety of work 90 can be accomplished by the arrangement described without requiring special and separate attachments, as is necessary in punch-presses and the like heretofore constructed.

Having thus fully described my invention, 95 I claim as new and desire to secure by Letters Patent—

1. A machine of the class described, provided with a punch-stock fitted to slide in the head, a pressure-pin carried by the said punch-stock, and a coupling for carrying the punch and screwing on the said punch-stock, to press the said pin in engagement with the head and to clamp the punch-stock in place on the head, substantially as shown and described. 100

2. A machine of the class described, having a head provided with a dovetailed slot, a punch-stock having a central hole therethrough and fitted to slide in said slot, a cap screwing upon said punch-stock, and a punch 110 having an enlarged section fitting within said cap and a bearing connection with the head through the hole in the punch-stock, substantially as described.

3. A machine of the class described, provided with a base-block formed with a longitudinally-extending dovetailed groove, a bolt having a head adjustable in the said groove, and a stripper engaged by the said bolt, and formed at its rear end with a foot resting on 120 the said base-block, substantially as shown and described.

4. A machine of the class described, provided with a base-block formed with a longitudinally-extending dovetailed groove, a bolt 125 formed with a dovetailed head fitted to slide in the said groove, a stripper engaged by the said bolt, and a gage resting on the said block, and engaged on the top by the said stripper, to securely hold the gage in place on the base-block, substantially as shown and described. 130

5. A machine of the class described, provided with a base-block formed with a longitudinally-extending dovetailed groove, a bolt

formed with a dovetailed head fitted to slide in the said groove, a stripper engaged by the said bolt, a gage resting on the said block, and engaged on the top by the said stripper, 5 to securely hold the gage in place on the base-block, and pins held transversely adjustable in the said gage, and adapted to be locked in place by eyebolts on the gage, as set forth.

6. A machine of the class described, provided with a head having a longitudinally-extending dovetailed groove, a dovetailed punch-stock fitted to slide in the said groove, and formed with a threaded projection, a coupling screwing on the said projection, and carrying the punch, and a pin fitted to slide in the said stock, and adapted to be engaged by the punch to move the pin against the head upon screwing up the coupling and drawing the stock in firm contact with the head, to 15 lock the stock in place, substantially as shown and described.

7. A machine of the class described, provided with a head having a longitudinally-extending dovetailed groove, a dovetailed punch-stock fitted to slide in the said groove, 20

and formed with a threaded projection, a coupling screwing on the said projection and carrying the punch, and a pin fitted to slide in the said stock, and adapted to be engaged by the punch, to move the pin against the head 30 upon screwing up the coupling and drawing the stock in firm contact with the head, to lock the stock in place, the said pin being formed with a head, for taking up the strain from the punch, substantially as shown and 35 described.

8. A machine of the class described, having a punch-stock fitted to slide upon the head and having a hole therethrough in the line of motion and giving access to the head, a cap 40 screwing upon the punch-stock, and a punch having an enlarged section within said cap and a bearing connection with the head through said hole, whereby the punch and punch-stock are firmly held upon the head, 45 substantially as described.
